UNITED STATES PATENT OFFICE

154,060

DESIGN FOR A COMBINATION CHEST AND
HUTCH

John Gordon Osborn, Sheboygan, Wis.

Application July 31, 1947, Serial No. 140,645

Term of patent 3½ years

(Cl. D33—19)

To all whom it may concern:

Be it known that I, John Gordon Osborn, a citizen of the United States and resident of Sheboygan, in the county of Sheboygan and State of Wisconsin, have invented a new, original, and ornamental Design for a Combination Chest and Hutch, of which the following is a specification, reference being had to the accompanying drawing, forming part thereof.

The single figure is a perspective view of a combination chest and hutch embodying my new design.

I claim:

The ornamental design for a combination chest and hutch, as shown.

JOHN GORDON OSBORN.
